(57) **CLAIM**

The ornamental design for a device for limiting blind, as shown and described.

DESCRIPTION

FIG. 1 is a front, right and top perspective view of a first embodiment of a device for limiting blind;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view thereof in a first configuration, wherein the device for limiting blind of FIG. 1 is limited;

FIG. 9 is a rear view thereof in a first configuration, wherein the device for limiting blind of FIG. 1 is limited;

FIG. 10 is a front view thereof in a second configuration, wherein the device for limiting blind of FIG. 1 is released;

FIG. 11 is a rear view thereof in a second configuration, wherein the device for limiting blind of FIG. 1 is released;

FIG. 12 is a front and top perspective view of a second embodiment of the device for limiting blind;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a front view thereof in a first configuration, wherein the device for limiting blind of FIG. 12 is limited;

FIG. 20 is a rear view thereof in a first configuration, wherein the device for limiting blind of FIG. 12 is limited;

FIG. 21 is a front view thereof in a second configuration, wherein the device for limiting blind of FIG. 12 is released; and,

FIG. 22 is a rear view thereof in a second configuration, wherein the device for limiting blind of FIG. 12 is released;

The broken lines in the drawings depict portions of the device for limiting blind that form no part of the claimed design.

The additional broken lines in FIGS. 9-11 and 19-22 depict environmental subject matter that forms no part of the claimed design.

1 Claim, 22 Drawing Sheets
